UNITED STATES PATENT OFFICE.

ARTHUR JOHN A. BELL, OF OKOTOKS, ALBERTA, CANADA.

RACK-CLEANING DEVICE.

Application filed May 12, 1924. Serial No. 712,335.

To all whom it may concern:

Be it known that I, ARTHUR JOHN A. BELL, a subject of the King of Great Britain, and a resident of Okotoks, in the Province of Alberta, Dominion of Canada, have invented certain new and useful Improvements in Rack-Cleaning Devices, of which the following is a specification.

My invention relates to improvements in rack cleaning devices, the objects of which are to provide a means capable of attachment to a grain separator and to be operated therefrom, by which weed seeds and the like, may be blown from grain racks when adjacent the separator to prevent such seeds being shaken onto the ground as the grain racks are being hauled back into the field for reloading and which accounts largely for the amount of weeds grown in subsequent crops of grain. A further object is to provide for such means being readily brought into engagement with a drive belt of the separator when required.

The invention consists essentially of a blower mounted on either side of a separator to which is fitted an air pipe having a flexible hose and a valved air nozzle for cleaning purposes, as will be more fully described in the following specification in which:

Fig. 1 is a view of a separator with my invention mounted thereon.

Fig. 2 is a perspective view of the blower and belt engaging mechanism.

Fig. 3 is a view showing a gear drive mechanism.

Fig. 4 is a view showing the air nozzle valve.

In the drawings like characters of reference indicate corresponding parts in each figure.

The numeral 1 indicates generally a grain separator having a straw blower belt 2 running over pulleys 3 and 4, one of which is driven from any suitable source. 5 indicates the feed hopper adjacent which the grain racks are drawn to discharge their loads of grain sheaves prior to being cleaned.

The numeral 6 indicates generally a blower (see Fig. 2) which consists of a pair of frame members 7 secured to the side of the separator 1 between which a pair of slide rods 8 are provided, a flanged bed plate 9 is slidably mounted upon the rods 8 and is resiliently supported by springs 10.

The numeral 11 indicates a casing bolted

to the plate 9 having a blower fan 12 mounted therein, upon a shaft 13 is rotatably mounted in a pair of journals 14 a drive pulley 15 is keyed to the outer end of the shaft which is adapted to be brought into engagement with the belt 2. A discharge outlet pipe 16 extends upwards from the casing 11 which terminates in a two branch bend 17 so that a hose 18 may be carried to both sides of the separator for convenience, to each hose I provide a tube 19 having a nozzle 20 at its outer end and at a convenient point in the tube I provide a pivotally mounted butterfly valve 21 (see Fig. 4) having an operating button 22 which is so shaped as to engage the slots 23 of a boss 24 secured to the tube to hold the valve in either open or closed position. 25 is a spring by which the button is held in resilient engagement with the boss. Driving communication is established between the blower 6 and the drive belt 2 by depressing the plate 9 and its parts by means of a screw 26 which extends through a threaded aperture 27 in the upper frame member 7, the screw is provided with a hand wheel 28 having peripheral slots 29 any of which are engaged by a spring latch 30 to prevent its turning by the vibration of the separator.

Should it be necessary owing to lack of space on the side of a separator to make a blower with a very small fan rendering high speed desirable, I provide a gear transmission as shown in Figure 3 in which a gear wheel 31 is keyed to the blower shaft engaging a driving gear 32 coupled to a driving pulley 33, which latter are rotatably mounted upon a stub shaft 34 carried upon a rocking arm 35 journalled at one end upon the shaft 13 and connected at the outer end to a nut 36 which has endwise movement along a screw shaft 37 suitably mounted from the separator wall and operated by a hand wheel 38. The rocking arm 35 on being raised by means of the screw 37 brings the pulley 34 into engagement with the belt, thus transmitting the drive through the gears 31 and 32 to the blower fan.

Having thus described the several parts of my invention I will now briefly explain its use.

The loaded grain sacks are brought to the separator and are ranged alongside the feed hopper 5 into which the sheaves of grain are thrown. The disturbance of the grain in the sheaves during its removal from the racks

to the feed hopper releases the weed seed therefrom and allows it to fall onto the parts of the racks. As each rack is emptied it is drawn forward to a point adjacent the blower where the nozzle 20 is used to direct the air from the blower 6 to any part of the rack desired to dislodge such seeds, thus avoiding the possibility of its being scattered during the return trip of the racks to the field.

When the two branch bend 17 is used with a pair of hose connections and the tubes 19, the valves 21 are kept closed except when one or both of the tubes and nozzles are in use.

If rack cleaning is not constantly necessary the drive between the pulley 15 and the belt 2 is disconnected by turning the hand wheel 28 to raise the blower upon the slide rods 8.

What I claim as my invention is:

1. The combination with a grain separator having a driving belt, of a guide frame secured to the separator body, a blower hav-

ing a drive belt adapted to be driven from the drive belt, said blower being slidably mounted upon the frame and means for moving the driving pulley into and out of contact with the driving belt.

2. A rack cleaning attachment for grain separators, comprising guide rods attached to the separator frame, a plate slidable on said rods, spring means serving to hold the plate in a predetermined position on said rods, means for shifting the said plate in the direction of and against the resistance of said spring means and a fan blower carried by and movable with the plate and including a pulley on the fan shaft adapted to engage or disengage a drive belt of the separator dependent upon the position of the plate.

Dated at Okotoks, Alberta, this 26th day of April, A. D. 1924.

ARTHUR JOHN A. BELL.
